UTILITY CART FOR HOUSE CLEANING
SOLVENTS AND APPLICATORS

Kenneth L. Wells, 5316 Harney Ave.,
St. Louis, Mo. 63120

Filed Aug. 12, 1971, Ser. No. 171,409

Term of patent 14 years

Int. Cl. D12—02

U.S. Cl. D12—29

FIG. 2

FIG. 1

FIG. 3

FIG. 1 is a view in elevation of a utility cart for house cleaning solvents and applicators, showing my new design;

FIG. 2 is a top plan view thereof;

FIG. 3 is a cross sectional view taken in the direction of arrows 3—3 of FIG. 1; and

FIG. 4 is a bottom plan view thereof.

I claim:

The ornamental design for a utility cart for house cleaning solvents and applicators, as shown.
